UNITED STATES PATENT OFFICE.

STEPHEN D. BAKER, OF NEW YORK, N. Y.

DESIGN FOR A BUILT-IN GRAB-RAIL WALL DEVICE.

51,196.

Specification for Design.

Patented Aug. 28, 1917.

Application filed February 6, 1917. Serial No. 147,004. Term of patent 14 years.

To all whom it may concern:

Be it known that I, STEPHEN D. BAKER, a citizen of the United States, residing at New York city, in the county of New York and State of New York, have invented a new, original, and ornamental Design for a Built-In Grab-Rail Wall Device, of which the following is a specification, reference being had to the accompanying drawing, forming part thereof.

The drawing shows a front perspective

view of my new design, the novel and ornamental features of which reside in so much of the device as is exposed to view when the same is in place in a wall.

I claim:

The new and ornamental design for a built-in grab rail wall device, substantially as herein shown.

In testimony whereof, I affix my signature.

STEPHEN D. BAKER.
